UNITED STATES PATENT OFFICE.

JOHN M. SCOTT, OF RACINE, WISCONSIN, ASSIGNOR TO OTTO R. BARNETT, OF CHICAGO,
ILLINOIS.

RAIL ANCHOR.

1,135,549.

Specification of Letters Patent. Patented Apr. 13, 1915.

Application filed August 26, 1913. Serial No. 786,646.

To all whom it may concern:

Be it known that I, JOHN M. SCOTT, a citizen of the United States, residing at Racine, in the county of Racine and State of Wisconsin, have invented certain new and useful Improvements in Rail-Anchors, of which the following is a specification.

My invention relates to devices for preventing the longitudinal creep of railroad rails, such devices being variously called rail anchors, anti-creepers or rail stays.

The object of the invention is to provide a device of this sort which will effectively prevent the rail from creeping under all conditions, which will not be loosened or displaced from operative position by the vibration of the rail, or other causes, which can be very easily applied to the rail without special tools and by the ordinary trackman, and which, besides possessing these requisites, can be manufactured at a very low cost.

More specifically and particularly, my invention seeks to improve upon rail anchors of the one-piece type by providing a form of device, consisting of a single integral casting, which will take a firmer, more reliable hold upon the rail than the one-piece anchors now in use, and which will be superior to such devices in certain other respects to be hereinafter set forth.

The invention is illustrated, in a preferred embodiment, in the accompanying drawings, wherein—

Figure 1 is a side view of the device fitted to a railroad rail, the rail being shown in section; Fig. 2, a sectional view taken on line 2—2 of Fig. 1; Fig. 3, a plan view showing the form and position of the device when first applied to the rail, and Fig. 4, a similar view showing the device bent so as to be fitted to the rail.

Like characters of reference designate like parts in the several figures of the drawings.

Referring to the drawings, A designates a railway rail having the usual base flanges a, and B one of the ties on which the rail is supported.

The anti-creeping device of my invention consists preferably of a single malleable iron casting formed so as to provide a jaw or rail engaging member C, a jaw or rail engaging member D, and a connecting member or cross bar E, the latter adapted to extend under the base of the rail. The jaw C, in the particular form of my invention

shown, is provided with a tie abutting member F which bears against the face or side of the tie B.

The application of the device to the rail is best shown in Figs. 3 and 4. The end of the cross bar having on it the jaw D is thrust under the rail and the jaw C fitted over one of the base flanges a with the tie abutting member F against the tie B. If desired the recess e of the jaw C may be formed so that the jaw has a wedging fit on the base flange in which case the jaw may be driven into place over the edge of the base flange by a hammer. The cross bar E is made long enough so that with jaw C fitted on one edge of the rail the jaw D will clear the other edge as shown in Fig. 3. The cross bar is made thin enough so that it will readily bend and the jaw D is brought into operative engagement with the rail by bending the bar as shown in Fig. 4. This may be done by hammering the jaw D toward the tie B. This hammering may be continued until both jaws make a tight fit on the base flanges of the rail. Preferably the device is so constructed that when fitted to the rail the jaw D stands away from the tie against which the jaw C bears. Therefore any tendency of the rail to creep is checked by the shortening of the distance between the jaws which the forward movement of the rail and the consequent movement of jaw D either by rocking on the fulcrum afforded by the abutment, or by the further bending of the bar E will involve.

The device above described has several very important advantages over the one-piece rail anchors now in use. One-piece anchors are desirable particularly because of low manufacturing cost and economy and convenience in shipping and handling. However, they have not proven as reliable in holding the rail or in resisting vibration and other causes tending to loosen and displace them as the devices which, by being made of two or more parts, provide means for effecting a positive grip on the rail. The one-piece anchor most commonly used consists of a rigid bar formed at opposite ends with jaws for engaging the opposite edges of the rail base and at one end with a projection or arm designed to bear against the face of the tie. The device is applied to the rail by rotating or turning it until both jaws are engaged with the rail base, the device being

so placed upon the rail that when rotated to its operative position the arm or projection will bear firmly against the tie. It will be readily seen that the conditions governing the application of the device to the rail, in the first place, make it a somewhat delicate matter to obtain the correct fit of the jaws to the rail and the arm or projection against the tie, and, in the second place, make it necessary that, if a tight grip is to be obtained at all, the device should be very accurately designed both as to the conformation of the jaw faces and also the precise length of the connecting bar. Because of the slope of the upper surfaces of the base flanges a slight variation from the intended angular position of the device will result in very materially decreasing the areas of contact between the jaws and the rail. When one considers that these devices are made in large numbers and of malleable castings which are likely to shrink or be otherwise deformed in the process of making, it will be seen that there is a considerable probability that even if applied to the rail in a skillful manner the devices will not, in all cases, take the requisite firm hold upon the rail either for the purpose of resisting the tendency of the latter to creep or to resist the various causes tending to shake the devices loose from the rail. Moreover, the very fact that the whole device has to be rotated in order to bring it to its operative position makes it impossible to obtain surfaces of contact with the rail of considerable area. My device, as above described, has none of these disadvantages. The surfaces of contact between jaw C, for example, and the rail may be made as great as necessary, the jaw may be driven upon the rail, and at the same time against the tie, and after this has been done the fitting of the other jaw D to the opposite edge of the rail does not involve any disturbance of the position of jaw C. As the jaw C does not need to change its angular position, as is necessarily the case with a device which, to be fitted to the rail has to be rotated as a whole, the recess of the jaw may have the same configuration as the edge of the base flange which it is designed to engage. This simplifies the design of the device and insures a more accurate and reliable fit. Furthermore, the device of my invention does not require any skill for its application to the rail.

With these prior devices the relations between the jaws are fixed at all times. Consequently, the device is removable by a reverse rocking movement and tends either to shift its position on the rail, or to drop off of the rail whenever it is no longer under a rocking tension with the abutment against the tie, as for example, when the contraction of the rail carries the abutment rearwardly from the tie. With my device, the

operative relation of the jaws to each other is different from their relative positions when the device is first applied to the rail, that is to say, the normal relation of the jaws is such that the device may be readily applied to the rail, whereupon, after they are applied to the rail, this relative position is permanently changed, whereby not only can the devices not be rocked in a reverse movement to remove them from the rail, but they are permanently held in such snug engagement with the rail that the device will not change its position on the rail even when the abutment is not in contact with the tie, but whenever the expansion or creeping of the rail brings the abutment in contact with the tie, the grip of the device on the rail will be such that any further tendency of the rail to creep will inevitably swing the outer jaw D toward the tie, thereby either further bending the bar E or, in case the bar should be too rigid for this purpose, then rocking the device as a whole upon the fulcrum accorded by the abutment. Preferably, however, the bar E, while of sufficient tensile strength not to break under creeping strains, will bend, thereby keeping the face of the abutment F over against the tie and preventing any tendency to rock the abutment so as to cut into the ties, this being an item of some importance where creosoted or other specially treated ties are used.

While I have shown and described a preferred embodiment I do not wish to be understood as limiting the scope of the invention to this particular form of anchor as the novel idea at the basis of the invention might be utilized in rail anchors quite differently shaped and constructed.

Wherever in the claim I have referred to any part of the device being "bendable to a permanent set," it should be understood that the term "permanent set" is used to differentiate this feature of my device from the bending of a spring or other resilient part as sometimes used in the prior art. In my device the "set" is permanent in the sense that it will retain the shape to which it is bent, although, with proper material, of course it can be thus bent and unbent repeatedly as may be required in successive applications of the device.

I claim:

1. A rail anchor comprising a connecting bar adapted to extend under a rail and provided at opposite ends with rail engaging jaws and at one end with a tie engaging abutment, all so arranged that the jaw on the end of the bar farthest away from the abutment will be held out of engagement with the tie, the connecting bar being bendable lengthwise of the rail to a permanent set to bring the jaws into operative engagement with the rail.

2. A rail anchor consisting of a single

5 malleable casting formed with means adapted to engage opposite sides of a railroad rail, and a connecting member for said means extending under the base of said rail, said 10 connecting member adapted to be bent after being applied to the rail so as to cause said rail-engaging means to grip the rail, said casting being also formed with a tie-engaging abutment at one end thereof arranged to hold the rail-engaging member at the other end thereof away from the tie.

3. A rail anchor comprising a pair of rail engaging members adapted to engage opposite sides of a railroad rail and a connecting member which is adapted to be bent by the creeping of the rail so as to bring said rail engaging members into tighter operative relation with said rail.

4. A one-piece rail anchor comprising a tie and terminating in a jaw adapted to engage the opposite edge of the base flange of 25 said rail, said bar being bendable to receive a permanent set so that after the device has been applied to the rail the jaws may be brought into operative relationship with said base flange.

5. A rail anchor consisting of a single integral casting formed to provide a jaw adapted to engage one edge of the base flange of a railroad rail having a tie abutting member, and a cross bar which extends 30 under the rail out of contact with said tie and terminating in a jaw adapted to engage the opposite edge of the base flange of said rail, said bar being bendable to a permanent set so that after the device has been applied 35 to the rail the jaws may be brought into operative relationship with said base flange.

JOHN M. SCOTT.
